UNITED STATES PATENT OFFICE.

HENRY J. OTTO, OF EVANSVILLE, INDIANA, ASSIGNOR OF ONE-HALF TO CHARLES W. HALSEY, OF EVANSVILLE, INDIANA.

FLASHER OR MAGNETIC ACTUATOR FOR SWITCHES AND THE LIKE.

Application filed May 27, 1927. Serial No. 194,786.

My invention relates to a flasher of the type adapted to operate signs, signals, mechanical toys and the like, and aims, among other objects, to provide an improved electro-magnetically operated device adapted for use with low voltages to close a circuit or to actuate a signal or sign, or the like, which is intended to function periodically.

In the drawings illustrating a selected embodiment of my invention;

Fig. 1 is an elevational view of a signal connected to be operated by my actuator;

Fig. 2 is a central, sectional view of an actuator embodying my improvements;

Fig. 3 is a central, sectional view taken on the line 3—3 of Fig. 2, and also indicating a wiring diagram;

Fig. 4 is a sectional view taken on the line 4—4 of Fig. 2; and

Fig. 5 is a view similar to Fig. 4 but showing the parts in different positions.

Referring particularly to the drawings, I have there shown my improvements as embodied in a flasher of the type in which an actuator in the form of a solenoid 10 carried in a suitable casing 11, is adapted to be energized periodically to cause the core 12 to give an impulse to means which controls the circuit to the solenoid and, at the same time moves or controls the movement of a sign, signal or the like.

Herein, the means actuated by the core 12 of the solenoid, comprises a shaft 13 journaled above the casing and to one side of the solenoid and an operating arm 14 is fixed at one end to the shaft so that it projects over the end of the upper end of the core. Referring to Figs. 2 and 3, I have shown balancing disks 15 mounted on one end of the shaft

and having a weight 16 on it so arranged that it normally holds the arm in position to be given an actuating impulse. On the other end of the shaft I provide means to actuate a circuit closing and breaking switch for energizing and deenergizing the solenoid. Herein, I have shown a cam or flanged disc 17 having a flat portion 18 adapted to cooperate with a pivoted arm or pallet 19 in much the same manner as an escapement wheel. Herein, this arm is shaped like a parallelogram. This arrangement is such that when the shaft is given an impulse by the solenoid core, the arm rides on the circular portion or high part of the cam with the switch open (Fig.

4), and when the arm is in the position shown in Fig. 5, the switch is closed.

In Figs. 4 and 5 I have shown a spring contact arm 20 connected to a binding post 21 suitably insulated from the casing. The lower end of the arm 19 is preferably bevelled and the free end of the spring arm 20 is bent upwardly so that the arm makes a wiping contact and, hence, is self-cleaning. The binding post 21 is connected to one end of the solenoid by a conductor 22 (see the wiring diagram in Fig. 3). The upper end of the arm 22 strikes a stop pin 23 in the form of a binding post or terminal, which is either grounded if a storage battery is used, or is connected to any source of low voltage current through a conductor 24. The other end of the solenoid winding is connected directly to the source of current through the conductor 25.

In order to insure that the pivoted switch arm 19 will strike the post 23 and close the circuit when the cam is turning counterclockwise as viewed in Figs. 3 and 4, I provide a pin 26 on a flange 27 of the cam adjacent the low part thereof so that the pin will strike the arm below the toe part and swing or knock it over against the post. Further, to keep the arm from swinging to the left too far to be engaged by the pin 26, I have shown a pin 28 on the casing adjacent to the upper end of the arm. As soon as contact is made by the rocker arm, the electromagnet is energized to give the shaft an impulse. The lower part of the cam permits the arm to keep the circuit closed an instant after the impulse is given to insure strong flux while the core is moving; then it strikes the toe of the arm and knocks it away.

To return the cam to a switch-closing position after the initial impulse is given to the shaft, I provide a leaf spring 29 suitably secured to the top of the casing and projecting upwardly at an angle to the horizontal. The upper end of this spring when struck by the actuating arm 14 will cause the arm to rebound. The arm and the weight 16 will be thrown back past their uppermost or vertical positions and, then they will turn the balancing disk by gravity to the switch-closing position.

To utilize the spring 29 also as a circuit-closing device or controller for a lamp, motor or other electrically controlled device, I have

shown a pair of stationary terminals 30 suitably carried by and insulated from the casing 11. These contacts are arranged to be bridged by an insulated end of the spring 29 5 and to close a circuit through conductors 31 and 32 connected to a source of electro-motive force whereby to flash on a lamp 33, start an operating motor 34 for a sign, signal or the like or for momentarily energizing any 10 electrical apparatus indicated diagrammatically at 35 or for operating all of them at the same time. To eliminate noise incident to the core 12 of the solenoid dropping in the casing, I provide a compression spring 36 in 15 a pocket 37 below the casing 10.

In Fig. 1 I have shown a hand pointer 38 mounted on a stand 39 simply for the purpose of illustrating one practical application of the invention. It may be assumed that the hand 20 pointer is either connected directly to the shaft 13 of my electromagnetic actuator or that it has a separate motor to operate it.

Obviously the present invention is not restricted to the particular embodiment thereof 25 herein shown and described. Moreover, it is not indispensable that all the features of the invention be used conjointly, since they may be employed advantageously in various combinations and subcombinations.

30 What I claim is:

1. A flasher of the character described comprising, in combination; an overbalanced oscillatory member; means for imparting motion to said member; a stationary contact 35 member; and resilient means serving to control the movement of the member and for closing and opening a circuit in which the contact member is connected.

2. A flasher of the character described comprising, in combination; a shaft having a 40 weighted member thereon; means for giving the shaft a turning impulse; means for arresting the movement of the shaft and returning it to a position where the weight will 45 cause it to return to its starting position; and a pair of contact members in a controlling circuit arranged to be bridged by the shaft-arresting means.

3. A flasher of the character described comprising, in combination; a shaft having a 50 weighted member thereon; and arm on said shaft; an electro-magnet below said arm and having its core arranged to give the arm and shaft a turning impulse; means for arresting the movement of the shaft and re-

turning it to a position where the weight will cause it to return to its starting position; and a pair of contact members in a controlling circuit arranged to be bridged by the shaft-arresting means. 60

4. A flasher of the character described comprising, in combination; an overbalanced oscillatory member; a solenoid having a core constructed and arranged to give said member an impulse; a stationary contact member; and 65 resilient means serving to control the movement of the member and for closing and opening a circuit in which the contact member is connected.

5. In a flasher device of the character described; a shaft; a weight for overbalancing said shaft means for giving rotary impulses to said shaft; means for arresting the movement of said shaft and returning it to position where the weight will cause it to return 75 to its starting position to receive another impulse; and means controlled by the movement of the shaft to energize the means for giving the impulse. 70

6. In a device of the character described; 80 a shaft; an oscillatory weight for overbalancing the shaft; a solenoid arranged to initiate rotary movement of the shaft in one direction; and resilient means for reversing the movement of the shaft whereby the overbalanced shaft is periodically oscillated. 85

7. In a device of the character described; a counterweighted shaft; an arm fixed on the shaft; a solenoid having a core arranged to give the arm an actuating impulse; means to reverse the movement of the shaft; a cam carried by the shaft; a pivoted switch arm arranged to be actuated by said cam; and a spring contact member cooperating with said switch arm. 95

8. In a device of the character described; a counterweighted shaft; an arm fixed on the shaft; a solenoid having a core arranged to give the arm an actuating impulse; a disk-like cam having a flat portion; a pivoted 100 rocker arm having an end portion adapted to conform to the periphery of the disk; a spring contact terminal arranged to have wiping contact with the arm; and a stop pin and terminal arranged to be engaged by the arm 105 when it is in contact with the spring contact terminal whereby to energize the solenoid.

In testimony, that I claim the foregoing as my own, I have hereto affixed my signature.

HENRY J. OTTO.
